Attorney.

UNITED STATES PATENT OFFICE.

JAMES LALLY, OF KENDALL, NEW YORK.

TRACE-BUCKLE.

SPECIFICATION forming part of Letters Patent No. 223,448, dated January 13, 1880.

Application filed November 3, 1879.

To all whom it may concern:

Be it known that I, JAMES LALLY, of Kendall, in the county of Orleans and State of New York, have invented an Improved Trace-Buckle, of which the following is a specification.

My invention relates to that class of devices known as "two-part buckles."

Heretofore trace-buckles have been formed in two distinct parts, and the parts connected, in practical use, by fastening one to a hame-tug and then passing its free end through the other part, and the end of a trace through both parts. The two distinct parts thus adjustably connected would become entirely separated when the trace was withdrawn.

My improvement consists in forming the two parts in such a manner that they can be adjustably and permanently connected, to secure all the advantages of a two-part buckle and to dispense with the disadvantages of becoming separated, all as hereinafter fully set forth.

Figure 1 of my drawings is a longitudinal section, showing my complete buckle applied. Fig. 2 is a perspective view. Together they clearly illustrate the construction, application, and operation of my complete invention.

a a are the parallel side bars of my buckle, bent at right angles at their rear ends. *b* is a bar that connects the front ends of the side bars. *c* is a bar of a wider dimension, that connects the rear and bent ends of the bars *a* on a different plane from the front end.

d represents a cross-bar in the center of the frame, cast solid therewith; or it may be in the form of a bolt that can be readily connected with the side bars, *a*, by screwing, riveting, or in any suitable way.

f represents a second frame, that is flexibly and adjustably connected with the oblong frame *a b c d* by means of loops *g g*, that are riveted to the frame *f*, or they may be formed

integral therewith. To thus connect the two frames, the loops *g g* are passed beneath the cross-bar *d* and their free ends passed up 45 through perforations in the frame *f*, and then riveted fast; or, when the loops are formed integral with the frame, the two frames are connected by means of a bolt being passed through the side bars, *a*, and through the loops, as required, to prevent them from separating when the trace is withdrawn from the two parts, and to allow lateral motion to the frame *f* for the purpose of freeing and adjusting the trace.

h is a rigid tongue projecting vertically from 55 the movable frame *f*, as shown.

In the practical operation of my buckle the hame-tug is secured to the front end of the frame *a b c d*. The back-strap and girth are next adjustably connected, by means of 60 buckles, to the ends of the movable frame *f*. Then the end of the trace is inserted at the rear end through the loop formed by the elevated bar *c* and passed over the movable frame *f*, that carries a vertical projecting 65 tongue, *h*, and into loops fixed upon the hame-tug, which it overlaps. By then pressing the trace down to engage the tongue in one of its central perforations, it will be connected with the buckle in such a manner that it can be 70 used for draft purposes, and also readily removed and adjusted relative to the hame-tug whenever desired.

I claim—

An improved trace-buckle having a body 75 composed of the parts *a*, *b*, *c*, and *d*, in combination with the interlocking adjustable frame *f g g*, having a tongue, *h*, all constructed and operating substantially as shown and described.

JAMES LALLY.
